United States Patent

Des. 237,544
Patented Nov. 4, 1975

237,544

MOTION PICTURE PROJECTOR OR THE LIKE

Dianne B. Ainslie, Rochester, N.Y., assignor to
Eastman Kodak Company, Rochester, N.Y.

Filed June 20, 1974, Ser. No. 481,288

Term of patent 14 years

Int. Cl. D16—02

U.S. Cl. D61—1 K

FIG. 1

FIG. 2

FIG.3

FIG.4

FIG.5

FIG. 8

FIG. 1 is a top plan view of a motion picture projector or the like, with the dust cover in a closed condition, showing my new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof showing the handle extended and the unit standing on the vertical support feet;

FIG. 7 is a front elevational view thereof showing the dust cover in an open condition and the viewing screen extended;

FIG. 8 is a top plan view of FIG. 7.

I claim:

The ornamental design for a motion picture projector or the like, as shown.
